UNITED STATES PATENT OFFICE.

WILLIAM J. MURPHEY AND OLIVER R. BURGESS, OF NEWCASTLE, INDIANA.

ELECTRIC WINDOW-SIGN.

1,096,448.

Specification of Letters Patent.

Patented May 12, 1914.

Application filed August 2, 1913. Serial No. 782,580.

To all whom it may concern:

Be it known that we, WILLIAM J. MURPHEY and OLIVER R. BURGESS, citizens of the United States, residing at Newcastle, in the county of Henry and State of Indiana, have invented a new and useful Electric Window-Sign, of which the following is a specification.

The object of our invention is to produce an electric window sign which may be readily mounted upon the inner frame of a window and held against the glass in such manner as to display any desired legend to the passer-by.

The accompanying drawings illustrate our invention.

Figure 1 is a front elevation of the device; Fig. 2 a side elevation showing fragmentary portions of the window frame and glass; Fig. 3 a rear elevation showing a fragmentary portion of the window frame and glass; Fig. 4 a horizontal section.

In the drawings, 10 indicates a box or receptacle of suitable size and of material acceptable to the Board of Fire Underwriters, said receptacle being in the form of an open faced box suitably ventilated as indicated at 11 and having its open faced frame 12 provided with grooves 13 for the reception of a legend-bearing card or plate 14 through which the lights may shine. The grooves 13 extend through one or more sides of the box or receptacle 10, as indicated in Fig. 2, to permit the ready insertion and removal of the legend-bearing card or plates 14. Arranged within the receptacle 10 are lamp sockets 15 in any desired number and arrangement and extending through the back of the receptacle is an ordinary connection fitting or socket 16.

Pivoted upon the back of receptacle 10, by means of a bolt 17, is a hinge bracket 18 provided with a pair of perforated ears 19, 19. Bracket 18 may be held in any desired angular position relative to receptacle 10 by the thumb screw 20 which passes through the bracket and into or against the rear wall of the receptacle 10. The receptacle 10 is supported upon a swinging arm conveniently formed of rod or wire into two projecting arms 22, 22 which are provided with inturned tips 23 adapted to take into the perforated ears 19 of bracket 18, said tips, when so placed, being held in place by any suitable means such, for instance, as a tie wire 32 connecting the two arms 22, 22 near

their ends. The supporting arm just described is pivotally supported in the outer ends of the arms 24, 24 of a U-shaped bracket 25 adapted to be secured by screws 60 or other suitable means 26 to a window or door casing 27, the arrangement being such that the open face of the receptacle 10 may be held against one face of the window light 28, by means of a spring 29 connected 65 at one end to bracket 25 and at the other end to one of the arms 22.

The structure described may be readily attached to existing window frames or door frames and, by turning the receptacle 10 70 upon bolt 17, the sign legend displayed by the card 14 may be given any desired position and any desired legend-bearing card may be inserted.

We claim as our invention:

1. In a device of the class described, the combination of a lamp-carrying receptacle having a legend-bearing face, a pivot bracket rotatably mounted on said receptacle so as to support the same to rotate 75 about an axis transverse to the legend-bearing face, a supporting arm hinged in said bracket on an axis at an angle to said first-named axis, and a supporting bracket hinged to said supporting arm and formed 80 for attachment to a suitable support.

2. In a device of the class described, a lamp-carrying receptacle having an open face provided with means for the reception of a legend-bearing card, a bracket pivotally mounted on the rear of said receptacle, releasable means for holding said bracket and receptacles from relative rotation about their connecting pivot, a supporting arm pivoted upon said bracket substantially at 85 right angles to the pivotal mounting of the bracket, and a supporting bracket pivotally connected with the supporting arm, said supporting bracket being formed for attachment to a window or door frame. 90

3. In a device of the class described, the combination of a lamp-carrying receptacle having a legend-bearing face, a pivot bracket mounted on the opposite side of said receptacle from said legend-bearing 95 face so as to support the receptacle, a supporting arm hinged in said bracket, and a supporting bracket hinged to said supporting arm on an axis different from that of the first mentioned hinge and formed for 100 attachment to a suitable support.

4. In a device of the class described, the

combination of a lamp-carrying receptacle having a vertical legend-bearing face, a pivot bracket mounted on said receptacle so as to support the same to rotate about a horizontal axis transverse to the legend-bearing face, a supporting arm hinged in said bracket on a substantially vertical axis, and a supporting bracket hinged to said supporting arm on a different substantially vertical axis and formed for attachment to a suitable support.

5. In a device of the class described, the combination of a lamp-carrying receptacle having a vertical legend-bearing face, a pivot bracket mounted on said receptacle so

as to support the same, a supporting arm hinged in said bracket on a substantially vertical axis, and a supporting bracket hinged to said supporting arm on a different substantially vertical axis and formed for attachment to a suitable support. 20

In witness whereof we have hereunto set our hands at Newcastle, Indiana, this 30th day of July, A. D. one thousand nine hundred and thirteen.

WILLIAM J. MURPHEY.
OLIVER R. BURGESS.
